UNITED STATES PATENT OFFICE.

PATRICK F. QUINN, OF SOMERVILLE, MASSACHUSETTS.

SEAT OR CUSHION.

SPECIFICATION forming part of Letters Patent No. 611,274, dated September 27, 1898.

Application filed April 19, 1897. Serial No. 632,759. (No model.)

To all whom it may concern:

Be it known that I, PATRICK F. QUINN, of Somerville, in the county of Middlesex and State of Massachusetts, have invented certain new and useful Improvements in Seats or Cushions, of which the following is a specification.

My invention relates to improvements in seats or cushions composed of wire springs; and its object is to lessen the use of hair and other materials with which seats or cushions are commonly filled, as they retain the heat of the person and are therefore objectionable.

15 My improved seat or cushion is composed of a series of wire springs similar in construction, having their upper and lower arms respectively connected and held together firmly in their relative positions by a flexible con-

20 nection, such as a coiled-wire spring, which, while holding the parts together, still is of sufficient resiliency to yield with the wire springs when weight is applied thereto, and when the weight is removed the wire springs 25 and the coiled-wire connecting-springs return the seat or cushion to its normal position.

30 My invention consists of certain novel features hereinafter described, and particularly pointed out in the claims.

In the accompanying drawings, which illustrate a construction embodying my invention, Figure 1 is a plan view showing the top of the cushion and the position of the wire springs. 35 Fig. 2 is an end view looking in the direction indicated by the arrow, Fig. 1. Fig. 3 is a detail view showing two adjacent and contiguous wire springs. Fig. 4 is a detail view of one of the wire springs.

40 Like letters of reference refer to like parts throughout the several views.

My improved seat or cushion is composed of a series of wire springs A, having the arms A', A², A³, and A⁴, and between the arms A² and A³ the wire is coiled in the form of a 45 spring-coil, as A⁵, the arms A² and A³ forming the V-shaped portion of the spring, with the coil A⁵ at the apex. The free ends of the arms A' and A⁴ have respectively a bent portion a and a'. The wire springs of the seat or cushion being similar, the seat or cushion is formed by placing said wire springs along-

side of one another and winding around the upper arms A' of each wire spring the coil B and around the lower arms A⁴ of each wire 55 spring the coiled-wire spring B'. This construction brings the bent portion a against the side of the arm A² at the top of the cushion and the bent portion a' against the side A³ at the bottom of the cushion, and said 60 coiled-wire springs B and B' hold said springs A firmly in position with relation to one another. As shown in Fig. 1, these springs are arranged around the edge of the seat or cushion, with the coils A⁵ extending inwardly and 65 out of the way, and in the center of the cushion there are two series of similar springs, which are connected together in a similar manner as those on the edges of the cushion and provide a bearing for weight at the center of the seat or cushion.

For convenience of manipulation the coiled-wire springs B and B' are provided for each edge of the cushion at the top and bottom, respectively, and across the cushion at the top 75 and bottom similar coiled-wire springs B³ and B⁴, respectively, are provided for connecting the upper and lower arms of the springs A around the center of the cushion in a manner similar to that shown in Fig. 3, and the opposite free ends of the coiled-wire springs B³ are 80 connected to the coiled-wire springs B, as shown at B⁵, and a similar connection is provided at the bottom of the seat or cushion for the coiled-wire springs B⁴. Strengthening 85 springs C extend across the top of the cushion and are connected at C' to the opposite coiled-wire springs B and also link with the central coiled-wire springs B³. (See Fig. 1.) Similar strengthening-springs are provided on the 90 bottom of the cushion, which are connected in a like manner to that shown on the top of Fig. 1.

When weight is applied to the top of the seat or cushion, the edges of the cushion and the arm of the wire springs A will be depressed vertically, and the coils A⁵ will move horizontally, and the cushion will adapt itself to the requirements of the weight, and upon the removal of weight the springs A and coöperating parts will return to their normal position, so that a strong, easy, and flexible seat or cushion is provided.

In order to change the shape of the edge, it

is only necessary to bend the upper arms A' and the lower arms A⁴ to the shape desired. Then the connecting coiled-wire springs B and B' will follow the shape given to the arms 5 A' and A⁴.

When the coiled-wire springs B and B' are wound upon the arms A' and A⁴, respectively, the ends a and a' and the arms A² and A³ firmly hold said coiled-wire springs B and B', 10 respectively, and prevent side motion or slipping of the springs A in the coils B and B', and the same construction is provided for the coiled-wire springs B³ and B⁴.

Where it is desired to have a stiffer edge 15 than is provided in the construction shown in the drawings, the ends a and a' can be formed into eyes at the top and bottom of the cushion, and flexible rods can be extended through said eyes along the edges and on the 20 inner side of the coiled-wire springs B and B'. Also, if desired, wire rods provided with eyes on the ends may be extended between and connected to the eyes formed on the ends a and a' of opposite springs in order to brace or 25 stiffen the seat or cushion.

I do not limit myself to the arrangement and construction shown, as the same may be varied without departing from the spirit of my invention.

30 Having thus ascertained the nature of my invention and set forth a construction embodying the same, what I claim as new, and desire to secure by Letters Patent of the United States, is—

35 1. In a seat or cushion, a series of wire springs provided with arms for forming an edge of said seat or cushion, a coil between the ends of said wire springs, flexible supporting means located around said arms and 40 connecting the same together to form a continuous edge of said arms and adapted to yield to the movement of said wire springs under the action of weight.

2. In a seat or cushion, a series of wire 45 springs having the upper arms thereof forming the upper edge of said seat or cushion, a coil between the ends of said wire springs, flexible supporting means consisting of coiled-wire springs located around said upper arms 50 and connecting the same together to form a continuous edge of said arms and adapted to yield to the movement of said wire springs under the action of weight, and a support for the lower arms of said wire springs.

55 3. In a seat or cushion, a series of wire springs having the upper and lower arms forming respectively the upper and lower edges of said seat or cushion, a coil between the ends of said wire springs, flexible supporting means located around said upper arms of said wire springs and connecting the same together to form a continuous edge of said arms and adapted to yield to the movement of said wire springs under the action of weight, and flexible supporting means located around said lower arms of said wire springs and connecting the same together to form a

continuous edge of said arms and adapted to yield to the movement of said wire springs under the action of weight.

4. In a seat or cushion, a series of wire springs having the upper and lower arms forming respectively the upper and lower edges of said seat or cushion, a coil between the ends of said wire springs, flexible supporting means consisting of coiled-wire springs located around said upper arms and connecting the same together to form a continuous edge of said arms and adapted to yield to the movement of said wire springs under the action of weight, and flexible supporting means consisting of coiled-wire springs located around said lower arms and connecting the same together to form a continuous edge of said arms and adapted to yield to the movement of said wire springs under the action of weight.

5. In a seat or cushion, a series of wire springs having the upper arms thereof forming the upper edge of said seat or cushion, a coil between the ends of said wire springs, flexible supporting means located around said upper arms and connecting the same together to form a continuous edge of said arms and adapted to yield to the movement of said wire springs under the action of weight, a support for the lower arms of said wire springs, and means for holding said upper arms and flexible supporting means in position with relation to one another.

6. In a seat or cushion, a series of wire springs having the upper and lower arms forming respectively the upper and lower edges of said seat or cushion, a coil between the ends of said wire springs, flexible supporting means located around said upper arms and connecting the same together to form a continuous edge of said arms and adapted to yield to the movement of said wire springs under the action of weight, means for holding said upper arms and flexible supporting means in position with relation to one another, flexible supporting means located around said lower arms and connecting the same together to form a continuous edge of said arms and adapted to yield to the movement of said wire springs under the action of weight, and means for holding said lower arms and flexible supporting means in position with relation to one another.

7. In a seat or cushion, a series of wire springs having the upper and lower arms forming respectively the upper and lower edges of said seat or cushion and extending in opposite directions, a coil between the ends of said wire springs, flexible supporting means located around said upper arms and connecting the same together and adapted to yield to the movement of said wire springs under the action of weight, and flexible supporting means located around said lower arms of said wire springs and connecting the same together and adapted to yield to the movement of said wire springs under the action of weight.

8. In a seat or cushion, a series of wire springs having the upper and lower arms forming respectively the upper and lower edges of said seat or cushion and extending in opposite directions, a coil between the ends of said wire springs, flexible supporting means located around said upper arms and connecting the same together to form a continuous edge for the top of said seat or cushion and adapted to yield to the movement of said wire springs under the action of weight, and flexible supporting means located around said lower arms and connecting the same together to form a continuous edge for the bottom of said seat or cushion and adapted to yield to the movement of said wire springs under the action of weight.

9. In a seat or cushion, a series of wire springs having the upper and lower arms forming respectively the upper and lower edges of said seat or cushion and extending in opposite directions, a coil between the ends of said wire springs, flexible supporting means located around said upper arms and connecting the same together to form a continuous edge for the top of said seat or cushion and adapted to yield to the movement of said wire springs under the action of weight, means for holding said upper arms and flexible supporting means in position with relation to one another, flexible supporting means located around said lower arms and connecting the same together to form a continuous edge for the bottom of said seat or cushion and adapted to yield to the movement of said wire springs under the action of weight, and means for holding said lower arms and flexible supporting means in position with relation to one another.

10. In a seat or cushion, a series of wire springs provided with arms for forming an edge of said seat or cushion, a coil between the ends of said wire springs, coiled-wire springs located around said arms and connecting the same together to form a continuous edge of said arms and adapted to yield to the movement of said wire springs under the action of weight.

11. In a seat or cushion, a series of wire springs each having a V-shaped portion with an upper arm bent at an angle to said V-shaped portion, a coil at the apex of each V-shaped portion, flexible supporting means located around said upper arms and connecting the same together and adapted to yield to the movement of said wire springs under the action of weight, and a lower support for said springs.

12. In a seat or cushion, a series of wire springs each having a V-shaped portion with an upper arm bent at an angle to said V-shaped portion, a coil at the apex of each V-shaped portion, flexible supporting means consisting of coiled-wire springs located around said upper arms and connecting the same together and adapted to yield to the movement of said wire springs under the action of weight, means for holding said upper arms and flexible supporting means in position with relation to one another, flexible sup-

wire springs under the action of weight, and a lower support for said springs.

13. In a seat or cushion, a series of wire springs each having a V-shaped portion with an upper arm bent at an angle to said V-shaped portion, a coil at the apex of each V-shaped portion, flexible supporting means located around said upper arms and connecting the same together and adapted to yield to the movement of said wire springs under the action of weight, a lower support for said springs, and means for holding said upper arms and flexible supporting means in position with relation to one another.

14. In a seat or cushion, a series of wire springs each having a V-shaped portion with an upper arm bent at an angle to said V-shaped portion, a coil at the apex of each V-shaped portion, flexible supporting means located around said upper arms and connecting the same together and adapted to yield to the movement of said springs under the action of weight, a lower support for said springs, and means on said upper arms with which said flexible supporting means engages for holding said arms and flexible supporting means in position with relation to one another.

15. In a seat or cushion, a series of wire springs each having a V-shaped portion with an upper and a lower arm bent at an angle to said V-shaped portion, a coil at the apex of each V-shaped portion, flexible supporting means located around said upper arms and connecting the same together and adapted to yield to the movement of said springs under the action of weight, and flexible supporting means located around said lower arms and connecting the same together and adapted to yield to the movement of said wire springs under the action of weight.

16. In a seat or cushion, a series of wire springs each having a V-shaped portion with an upper and a lower arm bent at an angle to said V-shaped portion, a coil at the apex of each V-shaped portion, flexible supporting means consisting of coiled-wire springs located around said upper arms and connecting the same together and adapted to yield to the movement of said springs under the action of weight, and flexible supporting means consisting of coiled-wire springs located around said lower arms and connecting the same together and adapted to yield to the movement of said wire springs under the action of weight.

17. In a seat or cushion, a series of wire springs each having a V-shaped portion with an upper and a lower arm bent at an angle to said V-shaped portion, a coil at the apex of each V-shaped portion, flexible supporting means consisting of coiled-wire springs located around said upper arms and connecting the same together and adapted to yield to the movement of said wire springs under the action of weight, means for holding said upper arms and flexible supporting means in position with relation to one another, flexible sup-

porting means consisting of coiled-wire springs located around said lower arms and connecting the same together and adapted to yield to the movement of said wire springs
5 under the action of weight, and means for holding said lower arms and flexible supporting means in position with relation to one another.

In testimony whereof I have signed my name to this specification, in the presence of two subscribing witnesses, this 6th day of April, A. D. 1897.

PATRICK F. QUINN.
